CLAIM

The ornamental design for a headwear with a set of hair ports, as shown and described.

DESCRIPTION

FIG. 1 is a rear perspective view of a headwear with a set of hair ports;

FIG. 2 is a bottom perspective view thereof;

FIG. 3 is a rear view thereof;

FIG. 4 is a right-side view thereof;

FIG. 5 is a left-side view thereof;

FIG. 6 is a bottom view thereof; and,

FIG. 7 is a top view thereof.

The broken lines depict portions of the headwear with a set of hair ports that form no part of the claimed design.
